UNITED STATES PATENT OFFICE.

ROBERT F. McGUIRE, OF GRAND FORKS, NORTH DAKOTA, ASSIGNOR OF ONE-HALF TO
R. B. GRIFFITH, OF GRAND FORKS, NORTH DAKOTA.

COMBINED BUNDLE CARRIER AND SHOCKER DEVICE.

1,220,866.

Specification of Letters Patent. Patented Mar. 27, 1917.

Application filed April 5, 1916. Serial No. 89,184.

To all whom it may concern:

Be it known that I, ROBERT F. McGUIRE, a citizen of the United States, residing at Grand Forks, in the county of Grand Forks 5 and State of North Dakota, have invented certain new and useful Improvements in Combined Bundle Carrier and Shocker Devices; and I do hereby declare the following to be a full, clear, and exact description 10 of the invention, such as will enable others skilled in the art to which it appertains to make and use the same.

My invention relates to new and useful improvements in combined bundle carrier 15 and shocker devices and my object is to provide a platform to be connected to any suitable form of grain harvester of the binder type and provide means thereon for conveying the sheaves or bundles of grain to one 20 end of the platform.

A further object is to provide a carrier frame in the rear of the platform upon which the bundles are deposited from the platform.

25 A further object is to provide means for causing the bundles to assume the form of a shock while resting upon the carrier frame.

A further object is to provide means for controlling the movement of the carrier 30 frame.

And a further object is to provide means for causing the shock formers to rotate in the arc of a circle when the carrier frame is moving to lowered position.

35 Other objects and advantages will be hereinafter set forth and more particularly pointed out in the accompanying specification.

In the accompanying drawings which are 40 made a part of this application,

Figure 1 is a detail side elevation of my improved form of bundle carrier and shocker showing the different position of the parts thereof by full and dotted lines.

45 Fig. 2 is a top plan view of the device, and

Fig. 3 is a detail end elevation of one of the shock forming members showing the manner of operating the same by parts of 50 the carrier frame.

Fig. 4 is a detail plan view of the operating means for raising and lowering the carrier frame.

Referring to the drawings in which simi-

lar reference numerals designate corresponding parts throughout the several views, 1 indicates a platform which may be constructed in any preferred manner and is so positioned as to receive the bundles of grain as discharged from the binder, said 55 platform having mounted thereon vertically extending shafts 2 and 3 upon which are mounted rollers 4 and 5 respectively, said shafts and rollers being arranged in pairs to receive endless belts 6 and 7 respectively 60 between which the bundles 8 of grain are adapted to pass and be conveyed from the platform 1 to a carrier frame 9 at the rear end of the platform. If it is found desirable, the belts 6 and 7 may be provided with 70 suitable cleats or projections whereby the gripping action of the belts with the sheaves of grain will be increased sufficiently to positively move the sheaves to the rear of the device.

The rollers 4 and 5 are operated from a shaft 10, said shaft having gears 11 and 12 thereon which mesh with gears 13 and 14 respectively on the lower ends of the shafts 2 and 3, the shaft 10 being driven through the 80 medium of a driving gear 15 attached to the axle 16 employed for supporting the platform 4 and a gear 17 fixed to the end of the shaft 10 and as the belts 6 and 7 are rotated in the same direction, the bundles, when engaged by said belts, will be deposited upon the carrier frame 9 and a plurality of bars 18 attached thereto.

Extending rearwardly from the platform 1 are frame bars 19 to the outer ends of 90 which are swivelly attached supporting casters 20 and between said frame bars is positioned the carrier frame 9, said carrier frame having side bars 21 at each edge thereof to which are attached supporting straps 22, the upper ends of said straps being attached to supporting rods 23, the ends of the supporting rods being in turn pivotally attached to the upper ends of standards 24.

The lower ends of the standards 24 are pivotally attached to the frame bars 19, and the lower ends of the forward standards are connected together by extending an integral section thereof transversely of the platform. 95 The carrier frame is raised and lowered by attaching any suitable form of operating means to a shaft 25, such as a foot lever 25^a

slidably mounted through a bearing 25^b pivotally mounted upon the frame of the binder. The shaft 25 is fixed to the upper end of one of the forward standards 24, 5 whereby the carrier frame can be held in its elevated position or lowered and raised at will, and in discharging the bundles from the carrier frame, it is but necessary to release the shaft 25 when the weight of the 10 bundles will cause the carrier frame to descend and engage the butts of the bundles with the ground, whereupon the continued forward movement of the carrier frame and parts to which it is attached will cause the 15 bundles to leave the carrier frame and at the same time remain in a set up position.

As soon as the bundles in shock formation are clear of the bars 18 of the carrier frame a forward pull is given to the shaft 25 which 20 will return the carrier frame to its elevated position to receive additional bundles of grain. In order to collect the bundles and form them into a substantially circular shock, a pair of coöperating shock forming 25 rods 26 and 27 are mounted in elongated sockets 28 and 29 respectively carried by supports 30 and positioned on opposite sides of the belts 6 and 7, the rear end of said rods developing into curved terminals 31 and 32 30 respectively, the terminal 31 and rod carrying the same being in a plane lower than the plane of the rod 27 and terminal 32 and the terminal 31 is positioned a distance in the rear of the terminal 32 so that when the 35 bundles strike said terminal the butt ends of the bundles may pass farther to the rear than the head ends thereof, thus causing the bundles to assume a slight leaning position toward the center of the shock whereby the 40 bundles will more readily remain in set up position when deposited upon the ground.

The curved terminals 31 and 32 are positioned adjacent the discharging ends of the belts 6 and 7 when the shock first begins to 45 form upon the carrier frame, and as additional bundles are forced on to the carrier frame the rods 26 and 27 move lengthwise through the sockets 28 and 29 respectively until the curved terminals have reached the 50 full limit of the carrier frame or until such time as it is desired to discharge the shock from the carrier frame, and after the shock has been discharged from the carrier frame the rods 26 and 27 are instantly returned 55 to their initial forward positions by means of springs 33 and 34 surrounding the rods 26 and 27 respectively between the sockets 28 and 29 and nuts 35 and 36, which nuts engage the threaded ends of said rods and may 60 be adjusted thereon to regulate the tension of said springs and the movement lengthwise of the rods.

In order to insure that the curved terminals 31 and 32 will move out of the path 65 of the shock as it leaves the carrier frame,

arms 37 and 38 are attached respectively to the shock forming rods 26 and 27 adjacent the juncture of the straight and curved portions of said rods, the outer ends of said arms having elongated slots 39 which engage 70 the supporting rods 23 and slide thereon, said arms causing the rods to which they are attached to move a quarter rotation when the carrier frame descends, thereby swinging the terminals 31 and 32 upwardly to a substantially 75 vertical position, as best shown by dotted lines in Fig. 1, thus disposing the same entirely out of the path of the shock.

In operation, as the bundles are fed on to the carrier frame by the belts, the rods 26 and 27 are gradually moved lengthwise through their respective sockets, and in view of the curvature of the terminals of said rods the bundles are collected into a substantially circular shock, and in view of the angle 85 assumed by the bundles, said bundles will rest in substantially vertical formation when deposited upon the ground. As soon as a sufficient number of bundles have been collected upon the carrier, the shaft 25 is released, whereupon the carrier frame will descend and deposit the bundles upon the ground, the descent of the carrier frame rotating the shock forming rods and elevating the curved terminals thereof out of the path 90 of the shock.

As soon as the shock is clear of the carrier frame, said frame is again elevated, thus restoring the curved terminals to their initial positions and at the same time the springs 100 surrounding said shock forming rods will return the rods to their initial forward positions and this operation is repeated indefinitely.

Having thus fully described my invention 105 what I claim as new and desire to secure by Letters Patent of the United States, is:—

1. In a bundle carrier and shocker, the combination with a platform, a carrier frame, and means to raise and lower the 110 frame, of a pair of rods slidably mounted upon the platform, said rods each having a curved terminal at one end, means to move the bundles from the platform against said curved terminals to increase the size of the 115 shock forming space on the carrier frame, and spring tension means to return said rods to their initial positions after being operated to form a shock.

2. In a bundle carrier and shocker, the 120 combination with a platform, and a vertically movable carrier frame, of a pair of rods slidably and rotatably mounted upon the platform, said rods each having a curved terminal at one end to form and retain the 125 bundles in shock formation upon the carrier frame, spring tension means to return the sliding rods to their initial positions, and means carried by the rods controlled by the movement of the carrier frame for rotating 130

the rods to dispose their curved terminals in a vertical position out of engagement with the shock when the carrier frame is lowered.

3. In a bundle carrier and shocker, the combination with a platform, a carrier frame, means to raise and lower the carrier frame, of a pair of brackets mounted on the platform, a rod slidably mounted through each bracket and formed with a curved rear end, said rods disposed in horizontal overlapping relation, an expansible coil spring arranged on each rod forwardly of the bracket, means threadingly connected to the forward end of each rod to regulate the ex-

pansive tension of each spring, means to 15 move the bundles into engagement with the said curved rod ends to increase the shock forming space, and means to rock the said curved rod ends to a vertical position when the shock has been formed.

20 In testimony whereof I have signed my name to this specification in the presence of two subscribing witnesses.

ROBERT F. McGUIRE.
